(57) **CLAIM**

The ornamental design for a medical bracket and clamp, as shown and described.

DESCRIPTION

FIG. 1 is a front perspective view of a medical bracket and clamp showing my new design, wherein a partial view of a hospital bed end and cables are shown in broken lines for illustrative purposes only and form no part of the claimed design;

FIG. 2 is a top view thereof;

FIG. 3 is a front view thereof;

FIG. 4 is a right side view thereof;

FIG. 5 is a rear view thereof;

FIG. 6 is a left side view thereof; and,

FIG. 7 is a bottom view thereof.
